J. W. G.

UNITED STATES PATENT OFFICE.

ANTHONY FRICKER, OF LAKewood, OHIO.

DISCHARGE MECHANISM FOR BITUMINOUS DISTRIBUTORS.

Application filed May 7, 1919. Serial No. 295,319.

To all whom it may concern:

Be it known that I, ANTHONY FRICKER, a citizen of the United States, residing at Lakewood, in the county of Cuyahoga and State of Ohio, have invented certain new and useful Improvements in Discharge Mechanism for Bituminous Distributors, of which the following is a specification.

This invention relates to discharge mechanism for bituminous distributors.

When distributing bituminous material or petroleum products over a roadway it has been customary to circulate the heated bituminous material through a manifold and discharge the same from said manifold under pressure through a series of ports or openings spaced along the manifold, each of which projects its own jet of material downwardly. Such an arrangement has been found necessary in order to provide the necessary controlling valve mechanism to regulate the flow without permitting the bituminous material to congeal or harden when the ports are closed or the flow stopped. In order to thoroughly cover the roadway with a uniform coating the ports or outlet openings from the manifold should be as close together as possible so as to insure overlapping of the jets one upon another. However, the necessity of providing operating mechanism for the valves has necessitated placing the valves farther apart than is desirable.

One object of the present invention is therefore to provide valve mechanism for controlling the flow from the manifold which permits the ports or outlet openings to be placed very close together and at the same time enables the valve devices to be easily manipulated, but nevertheless in a positive manner.

A further object of the invention is to provide improved valve mechanism for a distributing manifold including a plurality of sets or gangs of outlet ports or openings differing in size from each other, each of said gangs of openings being controlled by its own set of valve devices, thereby enabling the separate gangs to be independently operated for varying the quantity of material deposited without special adjustment of the pressure of the liquid or of the valve devices or discharge nozzles.

A further object of the invention is to enable varying quantities of material to be deposited upon the roadway but nevertheless to be distributed uniformly over its entire surface.

A further object of the invention is to provide an improved form of valve device for controlling the flow of material from the distributing manifold, said valve device being of such form and being so located on the distributor as to be in heat conducting relation to the heated liquid material circulated therethrough, whereby the valve body and ported parts are maintained hot so as to prevent chilling or congealing of the material or clogging of the valves when closed.

A further object of the invention is to provide a distributor for bituminous or similar heated liquid materials whose bottom wall is pierced at intervals to form hollow ported valve bodies integral with the distributor, whereby the valve bodies and the cooperating plugs therein are heated by the liquid material to prevent clogging of the ports.

Further objects of the invention are in part obvious and in part will appear more in detail hereinafter.

The invention comprises the construction and arrangement of parts hereinafter described and claimed.

In the drawings, which represent one suitable embodiment of the invention, Fig. 1 is a rear elevation; Fig. 2 is a cross section on the line 2-2, Fig. 1; Fig. 3 is a similar section on the line 3-3, Fig. 1; Fig. 4 is a bottom plan view of the discharge nozzle shown in Fig. 3; and Fig. 5 is a similar view of the discharge nozzle shown in Fig. 2.

The discharge mechanism shown in the drawings comprises a manifold 1, which is in the form of a hollow tubular member whose inner chamber 2 is connected by the supply pipes 3 and return pipe 4 to a reservoir (not shown) from which the liquid bituminous material is circulated under pressure by gravity or a pump through the manifold, as is usual.

Along its bottom the manifold is provided at intervals with discharge nozzles through which the material is discharged in the form of jets upon the roadway. These nozzles are in two gangs, marked respectively 5 and 6, the members of the two gangs alternating in order along the manifold. Each of said nozzles is a simple threaded member screwed into an opening in the bottom of the manifold and provided with a through-opening terminating at its bottom in an outlet or discharge port 7. The discharge ports of

the nozzles of one gang, say members 6, are larger in cross sectional area than the discharge outlets of the other gang, as shown by comparison of Figs. 4 and 5. The flow of material through each gang of outlets is controlled by a series of inter-connected valve devices. All of the valve devices in each gang are alike, so description of one will suffice for all of that gang, and the valve members in each gang are simultaneously controlled. However, the valve devices for the two gangs may differ from each other and each set of valve devices is controlled independently of the other.

Fig. 2 represents in detail one of the valve devices for controlling the gang of outlet openings through the nozzles 5. As illustrated each nozzle 5 has a bore to receive a valve stem 8 seating downwardly against a shoulder at the bottom of said bore and normally held to its seat by a compression spring 9. Valve rod 8 slides through a bushing 10 threaded into the upper portion of the manifold, and the joint around said stem is sealed by a packing 11 in a gland nut 12. Each of the valve stems 8 has a loose pivotal connection at its upper end with one arm of a bell crank lever 13. The other arms of said bell crank levers are pivotally connected to a common operating rod 14. By moving said rod to the right in Fig. 1 all of the valve stems 8 are elevated to open the outlets from the nozzles 5 and produce discharge from all of said nozzles. Since said nozzles are located at uniform intervals along the full length of the manifold a uniform coating of bituminous material is discharged over the roadway.

Fig. 3 illustrates the valve mechanism for controlling the outlets through the other gang of nozzles 6. Each of said nozzles has a threaded member screwed into the bottom of the manifold with its opening aligned with an opening 15 through the bottom manifold wall. At each nozzle the bottom manifold wall is thickened to form a valve body portion 16 having a tapered bore to receive a tapered plug 17 having a through port 18 therein, said plug being held in place by a nut 19 threaded upon its reduced end. The opposite squared end of each plug has connected thereto a lever arm 20, all of said lever arms being pivotally connected at their outer ends to a common operating member 21. In the position of the parts shown in Figs. 1 and 3 all of the tapered valves are closed, but if the rod 21 is moved to the left in Fig. 1 all of said valves are simultaneously opened, and as said valves are distributed at uniform intervals along the entire length of the manifold uniform distribution of bituminous material occurs over the entire roadway.

Since the discharge openings of the two sets of nozzles are of different size one gang

of openings can be used for a light coat of material and the other set of openings for a heavier coat of material, while a still heavier coat can be applied by opening both sets of outlets at the same time. Nevertheless it is unnecessary to vary the pressure of the supply, or to more or less choke or restrict the flow by a valve located in the supply conduit, nor is any adjustment of individual valve devices necessary.

The use of two different types of valve devices enables each set to be correctly operated independently of the other without interference between the operating devices for the two gangs. For example, the operating levers and rod for the valves shown in Fig. 2 are at the top of the manifold, while the operating devices for the other gang of the valves are at one side of the manifold. Moreover the first set of valve referred to are vertically sliding members, whereas the second set are horizontally disposed plugs. When the gland nuts 12 are considered the two sets of valves can therefore be located closer together than if all the valves were of the same type.

The valve arrangement shown in Fig. 3 also prevents any possible chilling or congealing of the material circulated through the distributor because the valve body and the ported plug are in close heat conducting relation to the material in the distributor. Consequently they are kept hot so that even if the valves are closed the material does not congeal in the ports. Also, by making the valve body an integral part of the bottom wall of the distributor, with the valve plug therein, not only are the valve parts kept hot but the construction is simple and can be made at lower cost than prior constructions for the same purpose.

What I claim is:

1. In a device of the character described, a distributing manifold provided with a plurality of gangs of discharge outlets, the outlets of each gang being distributed at intervals along the length of the manifold, and a plurality of separate controlling means, one for all of the outlets of each gang.

2. In a device of the character described, a distributing manifold provided with a plurality of gangs of discharge outlets, the outlets of each gang being distributed at intervals along the length of the manifold, and a plurality of separate sets of controlling devices, one for all of the outlets of each of the gangs, said controlling devices for one gang extending horizontally and for another gang vertically through said manifold.

3. In a device of the character described, a distributing manifold provided with a plurality of gangs of discharge outlets, the outlets in each gang being of uniform size but differing in size from those in another gang, the outlets of each gang being distributed at

intervals along the full length of the manifold, and separate controlling means, one for all the outlets in each gang.

4. In a device of the character described, 5 a distributing manifold provided with a plurality of gangs of discharge outlets, the outlets of each gang being distributed along the full length of the manifold, controlling means for one gang movable in one vertical 10 plane parallel to the length of the manifold, and controlling means for another gang movable in another parallel vertical plane.

5. In a device of the character described, 15 a distributing manifold provided with a series of outlets arranged in gangs, the outlets of each gang lying between outlets of another gang, and valve devices for the outlets of each gang, those for one gang extending vertically and those for another gang ex- 20 tending horizontally.

6. In a device of the character described, 25 a distributing manifold provided with a series of outlets arranged in gangs, the outlets of each gang lying between outlets of another gang, valve devices for the outlets of each gang, those for one gang extending vertically and those for another gang ex-

tending horizontally, and independent controlling means for the valve devices of each gang.

7. Discharge mechanism for bituminous or other heated liquid materials, comprising a distributing manifold provided with inlet and outlet connections for circulating heated material therethrough, the lower wall of said manifold being pierced at intervals to form 30 hollow valve body portions along which the heated material flows, and a rotary ported valve plug in each of said valve body portions.

8. Discharge mechanism for bituminous or other heated liquid materials, comprising a distributing manifold provided with inlet and outlet connections for circulating heated material therethrough, the lower wall of 45 said manifold being pierced at intervals to form hollow valve body portions along which the heated material flows, a rotary ported valve plug in each of said valve body portions, and a discharge nozzle for each 50 of said valves, said nozzles terminating in close proximity to said manifold.

In testimony whereof I affix my signature.
ANTHONY FRICKER.
